UNITED STATES PATENT OFFICE.

MELVILLE E. PETERS, GEORGE H. FATH, AND ALBERT F. MILLER, OF DENVER, COLORADO, ASSIGNORS TO THE PETERS PATENT RIGHTS COMPANY, OF DENVER, COLORADO, A CORPORATION OF COLORADO.

BLANK-FEEDER FOR GUMMING-MACHINES.

1,239,817.

Specification of Letters Patent. Patented Sept. 11, 1917.

Original application filed May 25, 1915, Serial No. 30,471. Divided and this application filed February 8, 1916. Serial No. 76,988.

To all whom it may concern:

Be it known that we, MELVILLE E. PETERS, GEORGE H. FATH, and ALBERT F. MILLER, citizens of the United States of America, 5 residing at the city and county of Denver and State of Colorado, have invented a new and useful Blank-Feeder for Gumming-Machines, of which the following is a specification.

10 Our invention relates to improvements in automatically operating blank feeders for feeding blanks to gumming, printing, and other blank paper or other blank material using machines, where blank pieces of paper, silk and other materials are used to cover boxes and packages or that are to have descriptive or other matter printed on them, or in which they are to be cut or crimped or 15 folded into different shapes or forms, and 20 the objects of our invention are:

First, to provide means by which a stack of blanks are fed automatically to an air suction blank gripping and feeding mechanism at such predetermined intervals as the 25 air suction blank gripping and feeding mechanism requires in order that the stack may be advanced within its operative blank engaging and feeding movements.

Second, to provide a simple and positive 30 operating mechanism for feeding blanks one at a time into any kind of a machine where they are put to further treatment for use.

Third, to provide means by which each 35 blank is lifted and separated one by one from the stack of blanks. And

Fourth, to provide a simple and inexpensive combined mechanical and air suction mechanism for feeding blanks.

40 A further object of our invention is to provide an automatic feeding mechanism that will feed dry blanks or dry printed labels of paper, silk, leather, or other suitable material in such a rapid and positive and 45 reliable a manner that any blanks or labels that have a corner or end turned under or crimped or becomes twisted and crooked and is in any way out of correct and straight alignment and order will be automatically 50 caught and carried out of the feeding mechanism without interrupting or stopping the regular continuous feeding cycle movement of the feeding mechanism.

We attain these objects by the mechanism illustrated in the accompanying drawings, 55 in which:

Figure 1 is a side elevation of the improved machine for feeding blanks to gumming, printing, and other blank using machines.

Fig. 2 is a side elevation of the opposite side of the machine from that shown in Fig. 1.

Fig. 3 is a front elevation of the same. Fig. 4 is a plan view thereof.

Fig. 5 is a vertical sectional view through one of the pneumatically operated blank feeding tubes, and its supporting arm, and showing the manner of its connection with its operating rack bar.

Fig. 6 is a side elevation of the pawl, ratchet, and cam mechanism for automatically effecting and controlling the upward movement of the blank stack supporting table.

Fig. 7 is an edge view of the same.

Fig. 8 is a sectional plan view showing a portion of the blank stack supporting table and its slideway and one of the laterally adjustable blank guide bars and its operating means.

Fig. 9 is a vertical longitudinal sectional view of a portion of the blank table frame and its slideway and one of the feed screws for raising and lowering the same.

Fig. 10 is a detail sectional view illustrating the mechanism for removing blanks which are delivered to the feed roller in a crooked or distorted manner.

Similar letters of reference refer to similar parts through the several views.

Our blank feeding mechanism consists of the side frames 1 and 2, which two side frames form what we term the blank stacking frame. These frames are secured by 95 any suitable means to the machine, whatever it may be, that our blank feeder is to feed blanks to. In these frames we journal in suitable bearings formed in them a shaft 3, on the opposite end portions of which gears 4 are secured. These gears mesh with gears 5 that are mounted on the lower ends of vertically disposed threaded rods 6, which are supported in lugs 7 of the frame and are threaded in nut bushings 8, that are secured 100 in recesses 9, formed in the opposite end por-

tions of a frame 10, that is slidably mounted in guideway slots 11 formed in the inside surfaces of the adjacent frames. This frame forms an integral part of a table 12, 5 which is slidably supported between the frames. A hand wheel 13 is mounted on one end of the shaft 3 which when turned rotates the shaft and through its gears 4 and the gears 5 of the threaded rods rotates 10 the rods in the fixed nut bushings and raises or lowers the table. This table is arranged to support a stack or pile of blanks such as is used for covering paste-board boxes for which use these blanks are fed from our 15 automatic blank feeding mechanism to a gumming machine, where they are coated with adhesive gum on one of their sides. An example of the application of our blank feeding mechanism to a gumming machine 20 is illustrated and described in our pending application Serial Number 30,471, filed May 25, 1915.

Our invention contemplates broadly the application of our automatic blank feeder 25 to all kinds of machines to which blanks of any kind of material and for any use are fed.

Across the supporting frames 1 and 2 of the table a right and left handed threaded 30 rod 14 is extended and journaled in said frames, one end of which extends beyond its adjacent frame and is provided with a turning crank 15. On the right and left hand threaded rod 14, double ended levers 16 and 35 17 are threaded to its end portions. The lower ends of these double ended levers are loosely and slidably mounted on a smooth rod 18, which extends across the frames and is journaled in them, and which acts as a 40 horizontal guide rod for the threaded double ended levers. The upper ends of these double ended arms are each provided with a vertical rod 19, and these two rods project up through slots 20 formed in and through 45 the table from its opposite side edges, and these two rods form vertical side guides for the stack of blanks on the blank holding table 12. These blank holding guides are laterally adjustable to move in unison to 50 ward or away from the center of the table by turning the crank 15 and they extend far enough above the top of the blanks to act as guides for the full height of the stack of blanks or of any part of it as the blanks are 55 fed to the machine.

The top of the table is flat but is tilted slightly toward the machine to which the blanks are to be fed, and a stack of the blanks 21 is placed on the table and they 60 stand slightly tilted toward the machine our blank feeder is to be attached to, owing to the tilting position of the table 12, which tends to cause them to lean against the vertically disposed bars 22, that are secured to 65 a cross-bar 23 that is attached to the insides

of the adjacent frames. This pile of blanks extends up to the air suction blank gripping mechanism, and the table is raised automatically by this blank feeding mechanism periodically as this blank feeding mechanism requires it within its operative movement. 70

On the end of the gear shaft 3 that extends through and beyond the side frame 2, a ratchet wheel 24 is secured, and on the outside of this ratchet wheel a hub 2^A is mounted loosely on the shaft, which is provided with an arm 25 that supports a spring actuated pawl 26 which is arranged to extend in operative meshing relation to the 80 ratchet teeth of the ratchet wheel 24, and beyond their inner edge and on the inside of the ratchet wheel a cam disk 27 is loosely mounted on the shaft 3, which has a smooth peripheral surface that is free from ratchet 85 teeth and that is enough larger in diameter than the ratchet wheel to normally be engaged by said pawl 26 which normally rests on it. This cam disk is provided with a recess 28 in its peripheral edge that is long 90 enough to equal the length of several of the ratchet teeth of the ratchet wheel. As the smooth edge of this disk is larger in diameter than the ratchet wheel, the pawl which is mounted in operative position on the ratchet 95 disk will not enter into mesh with its teeth only when the recess portion of the smooth rim of the cam disk is in the reciprocal path of the pawl 26. Consequently when this cam disk is moved so that its recess 28 registers opposite to the pawl, the pawl will engage the teeth of the ratchet disk and will turn it to the extent of several teeth, and the mechanism that moves this cam disk 27 and the pawl to operate the ratchet wheel to turn 100 the shaft 3 and thus raise and lower the table, is as follows: 105

A lever 29 is secured at one end to the projecting arm 25 formed on the pawl supporting hub 2^A, the opposite end of which 110 extends to and is connected to one end of a rock arm 30 which is pivoted at its opposite end to the adjacent side frame 2 of the paper stack machine. This rock arm is provided intermediate of its ends with a lug 31 115 to which a roller 32 is secured, that is engaged by a cam 33 that is formed on a disk 34 that is mounted on the shaft 35. Consequently the pawl carrying hub is given a partial rotative movement on its supporting 120 shaft by the cam 33 and the rock arm 30. The pawl 26 is rigidly secured to a pin 36 that extends through a lug 37 formed on the arm 25. This pin is provided with a spring 38 that is arranged to hold the pawl 125 in resilient tension against the smooth edge disk, and in engaging relation to the ratchet toothed wheel. The smoothed edge cam disk 27 is moved reciprocally on the table's operating shaft 3 in the following manner, to 130

- free the pawl so that it will engage the teeth of the ratchet wheel: A link 39 is secured at one end to it and at its opposite end it is secured to one end of a rock arm 40. 5 This rock arm 40 is pivotally attached intermediate of its ends by a bolt 41 to the adjacent side frame 2 of the blank stacking frame, while the free end of this rock arm is provided with a roller 42. This rock arm 10 is held in its operative position by a spring 43, which holds the lever against a pin 44 and which is secured at one end to it just above its link connecting end, and at its opposite end is secured to the frame 2. The 15 roller 42 of this rock arm is engaged intermittently by the lower end 45 of a rock arm 46, which is secured to the end of a shaft 47 that extends across and is journaled in the side frames of the blank stacking frame. 20 This rock arm 46 and this shaft 47 form a part of the operating means for the blank gripping air suction tubes 48 and their co-operating mechanism that operates the cam actuated ratchet and pawl raising and lowering table mechanism just described, and which is arranged and operates the ratchet and pawl mechanism as follows:
- The opposite end 49 of this rock arm 46 contains an aperture in which a swiveling 25 lug 50 is loosely secured, and the outer end of this lug is loosely and slidably mounted on one end of a rod 51, and against one end of a coiled spring 52. The opposite end of this spring bears against a collar 53, which 30 is secured upon the rod 51. The end of this rod 51 adjacent to the lug clip is provided with a collar nut 54 which can be adjusted to limit the lug on the rod toward its free end. The opposite end of the rod 51 is pivotally 35 connected to one end of a rock arm 55 that is pivotally connected intermediate of its ends by a bolt 56 to the side frame of the paper stacking machine. The opposite end of this rock arm 55 is provided with a roller 40 57 which is engaged by a cam groove which is formed in the cam disk 34 that is mounted on the shaft 35. On the shaft 47 a vertically disposed crank lever 58 is secured at one end, the upper end of which is pivotally connected to one end of a link 59, the opposite end of which is pivotally connected to one end of a rock arm 60 that is mounted intermediate of its ends on a rock shaft 61, that 45 extends across and is journaled in bearings 50 formed in the side frames of the blank stacking frame. The opposite end of this rock arm 60 terminates in a casing member 62 that supports slidably a toothed bar 63, as will be presently described.
- 55 This rock shaft 61 extends across the blank stacking frames, and a crank lever 64 is secured at one end to it; the end of this crank lever 64, is pivotally connected to one end of a connecting rod 65, that extends toward the bed plate 66 of the machine, and 60 its opposite end is connected to a rock arm 67 which is pivotally connected just above the bed plate 66 to the adjacent side frame 1 of the machine. The opposite end of this rock arm is provided with a roller 68, that 65 is arranged to be engaged by a cam groove 69, that is formed on a disk 70 that is mounted on the shaft 35. This cam 69 and its rock arm 67, together with the connecting rod 65 and the lever 64, impart an oscillating movement to the rock shaft that results in a rocking sliding movement being imparted to the blank engaging pneumatically operating air suction tubes and their supporting mechanism, 70 which are adapted to move down against the top of the stack of blanks, grip by suction the top blank of the stack of blanks, raise it up clear of the blanks below the top blanks, then move the blank that has been gripped 75 by suction forward and carry it down and deposit it directly on top of a suction box 71 of a feed roller, from which it may be taken by the mechanism of the machine to which our blank feeder is attached. If desired a suction box may be attached to the platen or to a feed roller as shown and the blank may be gripped and fed by the feed roller into the machine our blank feeder is attached to, it being optional with the user 80 as to the means he employs to take the blank away from where the suction tubes have deposited it. After releasing the blank at the platen, the blank picking up and carrying and depositing suction tubes return back 85 to the stack of blanks for another blank.
- We will now describe this new, novel and reliable pneumatically operating single blank feeding mechanism.
- A gear 72 is rigidly mounted on the rod 105 shaft 61, which meshes with the toothed rack 63. This toothed rack is slidably mounted in the casing member 62, which forms a part of the lower end of the rock arm 60. Consequently the supporting casing of this 110 toothed bar has a rocking motion that is imparted to it by the shaft 47. The gear 72 meshes in the teeth of the rack bar and the gear 72 imparts a reciprocal movement to the toothed bar independent of the rocking 115 movement of its casing, in which it is slidably mounted. To the forward end of this toothed bar, a cross bar 73 is secured, in the opposite end portions of which slots 74 are formed. In these slots clips 75 are adjustably secured by screws 76, while the clips 120 are slidably mounted on the cross bar. One end of these clips projects forward of the bar far enough to form supports for air tubes 48 which are secured to them preferably by being forced into them. The lower ends of these tubes are provided with short tubular members 77 that are larger in diameter than the tubes 48. These blank gripping ends of the tubes and the blank grip- 125
- 130

ping tubes themselves may be of any suitable shape but are preferably in the form of circular tubes of about a half inch in diameter but may be made larger or smaller 5 as desired, and they may be made of any suitable material. We preferably however construct them of metal.

We have preferably illustrated but two of these blank gripping, carrying and depositing sucker members, but more may be added 10 if desired.

These air tubes have an up and down combined rocking and reciprocal movement, which owing to the rock arm and its casing 15 and the toothed rack, results in forcing the air tube members down tightly against the surface of the top blank of the stack of blanks. Then after the tubes have been moved down against the blanks they are 20 lifted with the blank gripped to them. Then the tubes move upwardly and forward, which results in the front or advancing edge of the blank being carried upwardly and forwardly against the edge of a couple of 25 saw toothed scrapers 78, which are supported directly in front of and in the path of the forward or advancing edge of each blank as it is raised up by the sucker members. These saw toothed scrapers are secured to the vertical bars 22 that are attached to the cross bar 23 that extends across the insides of the side frames of the blank stacker.

These saw tooth scrapers comprise block shaped members that each has an upwardly 30 and forwardly curved face, that is engaged by the advancing edge of each blank which is pushed against it, and as the blank is raised, its advancing edge scrapes, rubs, vibrates and chatters from the point of one 35 saw tooth to the part of the next one as it is pressed over and against these scrapers. Having raised the blanks over the scrapers, the sucker members carry the blank on its forward stroke over to the sucker box of 40 the feed roller 79 and drop it down with its advancing edge directly over the line of air suction apertures in the suction box, where it is gripped down against the surface of the air suction bar of the feed roller by a 45 presser plate 80 which will be presently described. The pressure plate that holds the blanks against the air suction apertures 50 of the feed roller is arranged to press the blanks down against air suction apertures 55 81 while the air tubes are raised up from it at the time the air suction is cut off from these tubes so as to positively and instantly release the blank from the tubes.

The free end of this presser plate is arranged 60 to allow the advancing edge of the blanks to be passed freely and easily under it, and the plate is provided with a row of recesses 82 that are positioned to register over the air suction apertures of the suction 65 box of the feed roller. This plate is secured

on a rock shaft 83 which is actuated to fly down and engage the blank by a spring 84 which is operatively connected to it, and also by a rock arm 85 that is mounted on the rock shaft and engages a cam 86 that 70 is formed on a sprocket wheel 87 that is mounted on the shaft 88 which is connected by a chain 89 with a sprocket wheel on the driving shaft 35. The cam and rock arm mechanism are timed to raise the bar high 75 enough to allow the tubes to move a blank under it over the row or line of air suction apertures in the suction box of the feed roller, when the cam instantly releases the rock arm and the spring 84 throws the 80 plate down on the blank and holds it down with resilient pressure. This blank gripping plate 80 is provided with recesses that register over the air suction apertures of the air suction box of the feed roller, in order 85 that there may be an unobstructed passage-way for the atmosphere to the blank directly over the air suction apertures.

The sucker tube members thus pick up and scrape off the edges of each blank and 90 this action loosens and frees the next blank underneath the top one, should, perchance, from any cause, the next blank start to raise up and follow the top blank.

The operation of our automatic stack of 95 blanks feeding and crooked blank removing apparatus is as follows:

The air tube members pick up the blanks and deliver them to the suction box of the feed roller in quick succession about fifty 100 per minute, and the downward reciprocal rocking movement of the sucker members' supporting mechanism allows of an up and down pressure movement against the top of the stack of blanks, and the blank gripping 105 tubes and their reciprocating bar are arranged to feed several blanks off from the top of the stack before the stack feeding mechanism is moved by it to feed the stack up within the full limit of the tubes' blank 110 gripping up and down reciprocal movement. The blank gripping tube device does automatically engage the stack supporting table feeding mechanism just before it reaches the limit of its blank engaging and gripping 115 movement, and moves it sufficiently to start the table's feeding mechanism to feed the table upward sufficient to bring the top of the stack to the blanks within the full blank gripping movement of the air tubes, and this action of the blank gripping tubes and their supporting mechanism is accomplished 120 as follows:

As long as the tubes are gripping and feeding blanks within the limit of their 125 regular blank gripping movement, which for example we will say is ten blanks, its arm 49 of its rock arm 46 through the medium of its puppet 50 is reciprocated on the rod 51 against the spring 52 freely, and at 130

the same time the cam actuated rod reciprocates freely through the puppet. As the tubes however feed the ten blanks off the top of the stack one at a time, the arm 49 of the crank arm 46 travels a little farther in the direction of the arrow, and its long arm moves closer to the roller 42 of the rock arm 40, until finally when the tenth blank is fed off of the stack the stroke of the crank 5 arm on the spring 52 and rod 51 is of sufficient length to cause the end 45 of this crank arm at a sufficient distance to strike the roller and tilt the rock arm 40 and cause the link 39 to pull the cam 27 around 10 on its shaft far enough to bring its recess 28 to register opposite to the pawl, which allows the pawl, which has been resting on the smooth peripheral edge of the disk 27 and has been continuously reciprocated 15 throughout its stroke by its cam actuated rock arm 30, to drop into the recess and consequently into mesh with the ratchet teeth of the ratchet wheel, and move this ratchet wheel rotatively a distance of several teeth, 20 and as the ratchet wheel is secured to the shaft 3 it partially rotates this shaft, which through the medium of its gears 4 and the gears 5 on the threaded rods 6 rotates these rods and as they are threadedly attached 25 to the table, the table and the stack of blanks is raised, and this ratchet engaging and step by step turning movement of the pawl is continued as long as the crank arm's lower end has stroke movement enough to 30 strike the roller and cause the rock arm 40 to move the recess 28 of the cam 27 to register opposite to the pawl to allow it to drop into the ratchet teeth of the ratchet wheel 24. The instant the table and its stack of 35 blanks is raised up to the full limit of the feeding movement of the blank gripping tubes, the stroke of the lower end 45 of the crank arm is too short to strike the roller, and the cam is drawn back by the spring 43 which acts on the rock arm to cause the link 39 to push the cam 27 around on its shaft so that its recess 28 is out of the path of the pawl, which would then ride on its smooth peripheral surface. It will thus be seen 45 that the blank gripping and feeding tubes with their rocking and reciprocal supporting bar and coöperating mechanism automatically feed the stack of blanks to the tubes as they are needed. 50 It is essential that in addition to holding the blank down after the air suction tubes have deposited it on the air suction apertures of the feed roller, some positive means be provided for instantly removing the 55 crooked blanks from the feed roller, and this feature of our invention coöperates with the blank feeding movements of the air suction tubes in the following manner: To the back of the vertical bars 22 that 60 support the saw toothed scrapers, I secure 65 a pair of blocks 89, in the sides of which apertures are formed, that receive the opposite ends of a shaft 90 on which rollers 91 are formed at short spaces apart. The rollers are larger in diameter than the shaft, 70 and they form frictional idler rollers for a set of rollers 92 that are formed on a shaft 93 that extends across and between the side frames 1 and 2 and is journaled in them. One end of this shaft extends beyond the 75 frame and a round belt sheave 94 is secured on its end. The rollers 92 on the shaft 93 are set close enough to the idler rollers 91 to either bear against them or be close enough for them to grip and feed a blank 80 down between them. This belt sheave is provided with a round belt 95 that extends over suitable sheaves 96 and 97 that are properly mounted on the adjacent side frame, and the belt extends from these 85 sheaves 96 and 97 to and is mounted on a sheave 98 that is secured on a right angled shaft 99 that is operated by a clutch controlled power driven shaft 100, which operates the shaft 35 by a worm pinion and 90 gear. The crooked blanks are engaged by an oscillating plate 101 that is provided with projecting blades that strike the blanks and carry them down between the rollers 91 and 95 92, the blades of the plate being arranged to extend down between the ends of the rollers and between the stem and the shaft. This feature of our invention we carry 100 out in the following manner: Upon the hub portions 102 of the feed roller 79 we mount loosely two rock arms 103, the ends of which extend toward the feed rollers 91 and 92, and to them we secure the thin metal angular shaped plate 101, which extends across the entire length of the feed roller 79 from one rock arm 103 to the other. The free lower edge of this angular plate is provided with projecting blade portions 104 which are spaced at a 105 distance apart and are of a length that will enable them to pass between the ends of the rollers 91 and 92 and also down between the shaft 90 and the shaft 93. Consequently when they strike down against a blank they 110 fold it up and carry it directly between the rotating rollers, which instantly grip it and feed it through them, while these blades pass down between the ends of the rollers and the shafts far enough to positively 115 force the crooked blank between the rollers, which are rotating toward each other. This plate is normally held above and out of the blank feeding path of the air tubes and also out of the path of the blank presser plate, 120 and it is thrown down against a crooked blank in the following manner: The inner or lower ends 105 of the rock arms 103 are pivotally connected to one of the ends of a pair of connecting rods 106, 125 130

the opposite ends of which are secured to one end of a crank lever 107, which is secured on a shaft 108. This shaft extends across and is journaled in both frames 1 and 2, and extends beyond the frame 1, and on its outside end a crank lever 109 is secured, the free end of which is connected by a link 110 with the upper end of a rock lever 111, which is pivoted intermediate of its length 10 to the side frame 1. The lower end of this lever is provided with a roller 112, which engages a cam 113 that is formed on a disk 114, that is mounted on the shaft 35.

This automatic blank removing mechanism operates in the following manner:

The rollers are positioned between the stack air tube blank feeding mechanism and the air suction apertures of the feed roller, and they rotate continuously at all times. 20 The reciprocating plate also reciprocates at each cycle blank feeding movement of our feeder, or in other words, it reciprocates up and down from its position out of the path of the blanks to its position between the 25 rollers and the shafts that support the rollers between the feeding movement of each blank from the stack to the feed roller. Then as the blanks feed to the feed roller, all those blanks that are in proper orderly 30 alinement and are straight are gripped by the air suction apertures of the feed roller and are quickly fed by it into the machine our feeder is attached to, but any and every 35 and all blanks that happen to be fed to the air suction apertures of the feed roller in a crooked or twisted or disorderly alinement with the row of apertures in the air suction tubes of the feed roller so as to uncover one or more of those apertures, and consequently 40 break the suction and are tripped and stopped at that point, instantly receive the downward stroke of the reciprocal movement of this plate intermediate of its ends or lengths, and it is instantly doubled up 45 and carried by this plate down into these constantly rotating rollers, which grip it and feed it through them and discharge it from the machine, without interfering in any way, shape or manner with the regular 50 time movements of the feeding blanks, and of the blank feeding mechanism.

Our invention provides a very rapid and reliable feeder of blanks that are delivered to the machine our feeder is attached to in 55 straight orderly alinement, and while we have illustrated and described the preferred construction and arrangement of our blank feeder, we do not wish to be limited to it, as many changes might be made without 60 departing from the spirit of our invention.

Having described our invention, what we claim as new and desire to secure by Letters Patent, is:

1. A box covering blank feeder for blank 65 gumming machines, comprising a stack

holder, and means including an air suction member for gripping the top blank and sucker member for gripping the top blank and separating it from the stack and for feeding it to a receiving means, and means 70 including a plate for stripping it from said suction feed, and means including a vertically reciprocating blade for removing irregular alined blanks from the feeder mechanism before they are discharged from it. 75

2. In a box covering blank feeder for blank gumming machines, a blank feeding mechanism comprising means including a blade arranged to permit the feed of orderly alined box covering blanks and to stop disorderly alined blanks, and means for removing the disorderly alined blanks, said means comprising blank gripping and feeding rollers interposed in the blank feeding mechanism, said blade being arranged to strike 80 and push said disorderly alined blanks into said rollers, whereby said rollers feed said blanks between them and discharge them from the feeding mechanism.

3. In a box covering blank feeder for blank gumming machines, means including an automatic blank feeding mechanism comprising means including air suction blank gripping sucker devices arranged to feed orderly alined blanks, said devices being 95 provided with means for stopping disorderly alined blanks, and means for removing said disorderly alined blanks from the blank feeding devices, said means comprising rotating blank receiving and gripping 100 rollers arranged in the blank feeding mechanism, and a reciprocating blade arranged to strike the disorderly alined blanks and push them into and between said rollers, and means for operating said blade in proper 105 time relation to said blank feeding devices to strike said stopped disorderly alined blanks.

4. In a box covering blank feeder for blank gumming machines, a blank feeding 110 mechanism arranged to feed orderly arranged and straight feeding blanks and means for removing disorderly arranged and crookedly feeding blanks, said means comprising blank gripping rollers inter- 115 posed in the feeding path of the blanks, and a reciprocating blade arranged to move into and out of the path of said blanks to said roller and arranged to strike the disorderly arranged blanks and carry them into said 120 blank feeding rollers, whereby they are fed through the rollers and discharged from the feeding mechanism, means for rotating the blank feeding rollers, and means for reciprocating said blank striking blade. 125

5. In a box covering blank feeder for blank gumming machines, the combination with blank gripping sucker members for gripping orderly alined blanks and stopping the feed movement of disorderly alined 130

- blanks, of means for removing said disorderly aligned blanks, said means comprising rotating rollers, idler rollers against which said rotating rollers rotate in blank gripping and feeding relation, means including a power transmitting belt for rotating said rollers and a reciprocating blade arranged to reciprocate across the feeding path of said blanks below the blank gripping surfaces of said rollers, and means including cam controlled rock arm mechanism for reciprocating said blade.
6. In a blank feeder for blank gumming machines, the combination of the stack of blanks supporting and feeding table, with a blank feeding mechanism arranged to feed blanks one at a time from said stack to a predetermined discharging point, comprising a rock shaft, a gear secured thereon, a 15 rock arm loosely mounted on said rock shaft, a toothed bar reciprocally mounted in the lower end of said rock bar, adjustable air suction operating blank gripping cupped tubes carried by said toothed bar, said tubes being adapted to be connected to air suction producing mechanism, and means including cam operated rock arm mechanism for imparting a movement to said air suction tubes whereby they are caused to grip blanks by 20 air suction one at a time at the top of said stack of blanks and convey them to said discharging point.
7. In a blank feeder for blank gumming machines, the combination with the mechanism for supporting a stack of blanks, with the mechanism for feeding one blank at a time from said stack, said mechanism comprising a rock shaft, a rock arm loosely mounted on said shaft, the lower end of 25 which is provided with a casing arranged to slidably house a toothed bar, a gear wheel
- secured to said rock shaft in mesh with said toothed bar, a slotted cross bar secured to said toothed bar, air suction tubes adjustably secured to said bar, said tubes being 30 adapted to be connected to an air suction producing mechanism, said tubes being arranged to move down on top of said stack of blanks and grip the blanks one at a time and feed them to a predetermined discharging point.
8. In a blank feeder for blank gumming machines, the combination of the mechanism for supporting a stack of blanks, the air suction tubes, the pressure plate and the 35 vertically reciprocating, irregularly aligned blank removing blade, with a crank lever and rock shaft, a connecting rod secured to said crank lever, a crank arm connected at one end to said connecting rod, a roller on 40 the opposite end of said crank arm, a cam shaft on said gumming machine, a cam disk mounted on said cam shaft, and a cam on said disk arranged to engage the roller of said crank arm whereby said cam and rock 45 shaft's toothed bar supporting casing and said gear and toothed bar impart a vertically and horizontally rocking and reciprocal movement to said blank gripping air suction tubes that causes it to move down 50 on said stack of blanks and grip them one by one and convey them forward to said predetermined point.

In testimony whereof we affix our signatures in presence of two witnesses.

MELVILLE E. PETERS.
GEORGE H. FATH.
ALBERT F. MILLER.
